(57) **CLAIM**

The ornamental design for a waterproof case for a camera, as shown and described.

DESCRIPTION

FIG. 1 is a front perspective view of a waterproof case for a camera showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a top plan view thereof, showing the waterproof case for a camera in an open configuration.

The broken lines illustrating portions of the waterproof case for a camera form no part of the claimed design.
